UNITED STATES PATENT OFFICE.

WILLIAM D. LA BATT, OF CHICAGO, ILLINOIS, ASSIGNOR TO ELISHA J. CADY, OF OAK PARK, ILLINOIS.

MICROMETER CALIPERS.

Application filed June 5, 1922. Serial No. 566,043.

To all whom it may concern:

Be it known that I, WILLIAM D. LA BATT, a citizen of the United States, residing at Chicago, in the county of Cook and State of Illinois, having invented certain new and useful Improvements in Micrometer Calipers, do hereby declare that the following is a full, clear, and exact description of the same, reference being had to the accompanying drawing.

The invention relates to micrometer calipers for measuring the thicknesses of various materials, and especially for measuring the thicknesses or points of different grades of paper-stock in variations of one-thousandth part of an inch.

The invention consists in the matters hereinafter described and then pointed out in the appended claims, and its features are illustrated in the accompanying drawing in which,

Fig. 1 is a top plan view of the device showing the general arrangement of parts;

Fig. 2 is a detail top plan view of the casing or housing with associated elements, parts being removed and broken away;

Fig. 3 is a detail horizontal sectional view through the casing taken on the line 3-3 in Fig. 6, parts being broken away;

Fig. 4 is a similar detail view of parts of Fig. 3 illustrating the lost-motion connection between the operating handle and the actuating shaft with parts in elevation;

Fig. 5 is a vertical sectional view on the line 5-5 in Fig. 1;

Fig. 6 is a detail vertical sectional view on the line 6-6 in Fig. 2; and

Fig. 7 is a detail horizontal sectional view on the line 7-7 in Fig. 6.

In the drawings the reference numeral 1 represents the base having a lower central anvil 2 and supporting a curved bracket-arm 3 which carries at its upper end a suitable circular block 4 provided with a central opening concentric with the anvil 2. A suitable casing or housing 5 is constructed with an upper circular chamber 6 and a lower circular well 7 concentric with the upper chamber but of reduced diameter, the vertical wall 8 of the reduced well 7 fitting into the central opening of the block 4 and extending in further reduced diameter below the block to form a circular bushing or annulus 9 in line with the anvil 2. A mounting plate 10 is secured in central position on

the floor of the upper chamber 6 over the upper end of the well 7, and is provided with an opening in the axial line of the well to afford a bearing for the screw-shaft 11; the upper plain portion of this shaft is 60 revolvably mounted in the plate 10 but is held therein against longitudinal displacement by the upper pinion 12 and the lower set-collar 13 fixed thereon. The upper end of the shaft passes freely through a dial-plate 14 above

which it carries a pointer 15; the dial-plate is fixed to the upper flange of the casing and is provided with an indicating scale on which the graduations or divisions are marked clockwise in units from zero to 100 70 as shown in Fig. 1, and above the pointer and upper end of the shaft a glass closure-plate 16 is spaced from the dial-plate by an intermediate head 17, these parts being held in position on the flange of the casing by a 75 flanged retaining ring 18 secured thereto.

The lower portion of the shaft 11 is screw threaded and engages the correspondingly inferiorly threaded upper end of a plunger 19 which extends from the well 7 down 80 through the annulus 9 and carries at its lower end a measuring anvil or foot 20 in vertical alinement with the stationary anvil 2. The threads on the screw-shaft and

plunger are ten (10) to the inch so that the 85 plunger moves vertically one-tenth (1/10) of an inch at each revolution of the screw-shaft and pointer 15, or one hundred points of one one-thousandth of an inch each. The

plunger 19 has a sliding fit within the annulus 9 but is held normally against rotation therein by a guide-collar 21 fitting on its shouldered upper end and slidably engaging a post 22 fixed in the plate 10 and projecting down into the well 7. The collar 21 95 preferably is split and its free ends are drawn together by the transverse screw 23 to frictionally engage the plunger, the engagement of these parts being tight enough to hold the plunger from turning under normal operations of the machine but allowing the plunger to be turned in the collar by a proper spanner-tool (not shown) when it is desired to adjust the plunger on the screw-shaft to set the foot 20 on the anvil 2 when

the pointer 15 is at zero on the scale; in other words, in setting up or calibrating the instrument the plunger may be turned by the spanner to overcome the friction of its guide 100 collar and revolve it on the screw-shaft one 105

110

way or the other until its adjustment is completed to bring the anvils together when the pointer 15 is at zero on the scale.

The anvil 2 preferably is universally adjustable in the base and for this purpose it is mounted therein by a ball and socket joint or bearing. The body of the anvil is rounded or convex and fits in a correspondingly curved or concave seat 2^a in the horizontal web of the base, being held against displacement therein by a tap-bolt 2^b threaded therein at its inner end and passing through an opening 24 in the bottom of the seat where its head engages a washer 25 having a concave inner face frictionally engaging the convex outer face of the seat. The inner face of the washer and the inner and outer faces of the seat are curved concentrically with the curvature of the body 10 of the anvil; the curvatures of the co-operating parts are struck on arcs of circles having radii of unequal lengths described from the center of the upper plane face of the anvil, as shown at *x* in Fig. 5, so that the anvil can be moved in any direction in its seat to adjust its face in any angular position. This adjustability of the anvil enables the machine to be set absolutely at zero as the face of the lower anvil thus 20 is brought into alignment with the measuring foot when the latter is set down upon it by turning the sleeve 19 with the spanner as above described; the opposing plane faces of the anvil and foot are in flush engagement.

The pinion 12 on the screw-shaft meshes with a larger gear-wheel 26 fixed on the lower end of a sleeve 27 which is revolubly mounted in the chamber 6 on a stud-shaft 28, and a small pinion 29 fixed on the upper end of the sleeve meshes with a larger sector-gear 30 which is fixed on the upper end of a vertical actuating-shaft 31 that is mounted in an upright bearing 32 secured in the plate 10. The shafts 28 and 31 are on opposite sides of the screw-shaft, and the sector-gear is cut-away to clear the latter shaft; the ratio of the gear is such that for each stroke of the actuating-shaft the screw-shaft and pointer will make more than three revolutions. The actuating-shaft 31 is located beyond the outline of the vertical wall 8 of the well 7 so that its lower end extends through the bottom wall of the chamber 6 and rests in a seat 33 in the block 4, and the outer face of the block is cut-away to form an angular recess 34 about the shaft 31 to movably receive the inner end of the operating handle 35 which is connected 40 to the actuating shaft 31. When the foot 20 is closed down upon the anvil 2 the handle 35 stands out in the position shown in Figs. 1 and 2 and in full lines in Fig. 3, with its front stop-shoulder 36 against the corresponding short wall of the recess

34; to open or separate the foot from the anvil the handle is moved inwardly more or less according to the degree of separation required, and when the handle is swung to its extreme inward position its rear stop-shoulder 37 abuts against the long wall of the recess 34 as shown in dotted lines in Fig. 3. The sector-gear 30 carries a radial arm 38 to which one end of a retractile coil-spring 39 is fastened, its other end being secured to a pin 40 in the chamber 6; when the handle is moved to its inner position to move the sector-gear to raise the screw-shaft the spring is put under tension, and when the handle is released the spring retracts the sector-gear and lowers the screw-shaft to position to bring the foot 20 into engagement with the material or stock on the anvil, or to close the foot on the anvil when no material is being measured. When the foot 20 meets the resistance of the stock or fabric on the anvil 2, the thrust-collar 13 on the screw-shaft takes up the pressure.

The handle 35 preferably has a return lost-motion connection with the shaft 31. For this purpose the lower end of the shaft 31 is cut-away or faced-off for about half its diameter to provide a flat transverse face as shown at 41, and the hole in the handle into which this portion of the shaft fits is provided with an abutment plate 42 arranged at an angle to the face 41, the parts being disposed so that the outer end of the abutment bears against the outer edge of the face 41 when the parts are in their normal positions with the anvils closed, as shown in full lines in Fig. 3. Now when the handle is swung inwardly the outer end of the abutment presses on the face and turns the shafts 11 and 31 clockwise. When the handle reaches its inward position its stop 37 hits the frame, but the lost-motion connections between the handle and shaft allows the latter to make any overthrow that may be caused by the momentum of the moving parts; the throw of these parts is taken up by the spring 39, and the blow of the handle against the frame is not transmitted to any of the interior parts. Also, this lost-motion connection allows the handle to be thrown back to its normal position without operating or affecting the shaft 31, and so without disturbing the interior parts; this is advantageous as it frequently happens that while stock or material is between the anvils and so the screw-shaft cannot descend the handle is inadvertently retracted by a careless operator or is accidentally struck, and with the lost-motion connection neither occurrence affects the actuating shaft and so produces no unusual strain or stress on the parts. The handle can be returned to its normal position regardless of the positions of the other parts, and when the stock

is removed from between the anvils the spring 39 will restore the other parts to their normal positions as shown in Figs. 1 and 2 and in full lines in Fig. 3. In practice the lower end of the shaft 31 is case-hardened and the plate 42 is made of tempered steel to obviate wear and play between the parts.

The return of the parts to their normal positions by the force of the spring 39 is controlled by a centrifugal governor. The plate 10 is provided at one side of the line of the shafts with a shallow circular pit 43 in which a shaft 44 is axially mounted with its upper end in a bearing-bracket 45 carried at the top of a vertical post 46 in the chamber 6, and the shaft is provided with radial-rods 47 in the pit on which weights or discs 48 are slidably mounted to move outward by centrifugal force and frictionally engage the inner face of the wall of the pit when the shaft 44 is rotated. The shaft 44 carries a fixed pinion 49 in mesh with a gear-wheel 50 revolvably mounted on the shaft 11 above the pinion 12, and the gear-wheel 50 carries on its underside a spring-pressed pawl 51 adapted to wipe idly over the teeth of the pinion 12 when the latter is turned by the handle in the direction to move the pointer 15 clockwise on the scale and raise the foot 21, and to engage a tooth of the pinion 12 and move with it when it is retracted by the spring 39 to lower the foot 21. The teeth of the pinion 12 are formed to thus co-operate with the pawl which is pivoted on the wheel 50 at 52 and is held against the teeth of the pinion 12 by a spring 53 mounted thereon; a front stop 54 prevents the pawl from bottoming in the teeth of the ratchet 13 which affords an advantage in assembling the machine as the pawl then will drop into the ratchet at any point, and a rear stop 55 keeps the pawl from being thrown out of operative relation by centrifugal action while allowing it to clear the ratchet. When the handle is turned to raise the foot 20 the pinion 12 turns away from the point of the pawl which wipes over it so that the pawl-carrying gear 50 is not rotated, and hence the governor is inactive. When the handle is released the retracting spring 39 turns the sector-gear 30 back toward its normal position and reversely rotates the pinion 12, and the pawl-carrying gear 50 is correspondingly rotated by its pawl engaging the pinion 12, the shaft 44 is rotated rapidly and the governor weights 48 frictionally engage the wall of the pit; the governor takes control of the closing of the foot 20 on the stock or on the anvil 2, and retards the return of the parts by the force of the spring 39, so that the foot 20 is not brought down with a blow and the parts are not subjected to a corresponding strain or shock. The centrifugal governor regu-

lates the descent of the plunger so that its speed is uniform throughout its down travel and its impact is always of the same force; also, this feature enables the throat of the arm 3 or the passageway between the base 1 and block 4 to be extended or deepened to any extent necessary to receive very large sheets of stock or material to calibrate them at any point in their area.

The machine is also provided with a trip indicator to show the number of revolutions of the pointer 15 or the number of hundred points of separation between the anvils. The actuating shaft 31 carries an indicator sector-plate 56 which moves below a correspondingly shaped slot 57 in the dial-plate 14. The sector-plate 56 carries an indicating mark 58 which when the machine is assembled or calibrated is placed in register with a zero mark on the dial-plate 14 near one end of the slot 57; the plate 56 is frictionally held on the shaft 31 so that this adjustment is readily made. The dial-plate 14 also carries the numerals 100, 200 and 300 arranged at suitable distances along the slot 57; the indicator sector and its associated marks are correlated with the gradations on the dial 14 in accordance with the ratio of rotation of the actuating shaft 31 and the screw-shaft 11. When the instrument is closed the trip mark 58 stands at zero; when the pointer 15 has made one revolution or trip and the distance between the anvils is 1/10 of an inch the mark 58 stands at 100 indicating that the separation between the anvils will measure 100 points of 1/1000 of an inch each; when the pointer has made two revolutions or trips the mark stands at 200, and when the pointer has made three revolutions or trips the mark stands at 300. When the anvil is raised the mark 58 moves to corresponding position, and when the anvil 20 is set down on the material resting on the lower anvil 2 this mark will show the number of revolutions or trips of the pointer 15 at which the reading is taken; for example, for stock greater than 2/10 of an inch in thickness and for which the anvil 20 must correspondingly rise and the pointer 15 must make more than two revolutions or trips, the mark 58 stands beyond 200 and the pointer 15 stands at the point (say 35) on its dial equal to the excess beyond 200 corresponding to the thickness of the material in excess of 2/10 of an inch, and so the two indicators 48 and 15 give the total reading of 235 points for the sample being calibrated.

In using the machine, the parts normally stand in the position shown in Figs. 1 and 2, with the measuring foot on the anvil, the pointers at zero, and the handle swung out. Upon moving the handle inwardly the shaft 31 is oscillated and the gear 30 moved to rotate the shaft 11 whereby the

foot is raised and the pointers moved on the scales. If the handle is moved to its limit the shaft 11 and pointer 15 will be given slightly more than three full revolutions and the pointer 58 will be moved slightly beyond 300, and if the stock to be calipered is now inserted on the anvil under the foot and the handle is released the spring 39 will return the parts toward their normal 10 positions until the foot reaches the stock on the anvil, when their further movement will be arrested and the pointers will stop on the dials. When caliperig heavy or thick 15 grades of stock it will stop the descent of the foot when the pointer 58 is past one of its indicating units, say between 200 and 300, and this pointer will then indicate that the stock exceeds the measurement of the unit 200 and the pointer 15 will indicate the 20 intermediate unit or point, so that the indication and reading of the measurement of the stock are direct and without any computation by the operator. When the stock to be calipered is thin or light the movement of the pointer 15 need not exceed the point to raise the foot far enough to allow the stock to be inserted on the anvil, the screw-shaft need not necessarily be given a full revolution, but in any event the descent 25 of the foot 20 is arrested by the stock with the pointer 15 on the appropriate unit to give direct indication and reading of the thickness of the stock. In any use of the machine the centrifugal governor opposes 30 and modifies the force and quick action of the return spring 39 and cushions the return of the foot 20 on the anvil or stock so that there is no blow of the foot and no shock or strain on any of the parts of the machine.

40 I claim:

1. In a caliperig device, a base, an anvil, a ball and socket joint connecting the anvil and base, a measuring-foot, a movable handle, a scale and revoluble pointer, a shaft actuating the pointer, operating connections between the shaft and foot, and gear connections between the shaft and handle to operate the former when the latter is moved.
2. In a caliperig device, a base, a seat in the base provided with a vertical hole and having concentric inner and outer faces, an anvil having a plane face and a body curved to fit the inner face of the seat, a washer 45 curved to fit the outer face of the seat, a tap bolt in the hole connecting the washer and anvil, a measuring foot having a plane face opposite the face of the anvil, a scale and revoluble pointer, a handle, and operating connections between the foot, the pointer and the handle.
3. In a caliperig device, a frame having an anvil and an upper chamber, a screw-shaft in the chamber, a pointer on the shaft, 50 a dial for the pointer, a plunger threaded

on said shaft and slidably actuated thereby and carrying a measuring foot, a split collar in the chamber held against rotation and frictionally engaging the plunger, and means to rotate the shaft. 70

4. In a caliperig device, a frame having an anvil and an upper chamber, a screw-shaft in the chamber, a pointer on the shaft, a dial for the pointer, a plunger threaded on said shaft and slidably actuated thereby 75 and carrying a measuring foot, means to rotate the shaft, and means constructed to hold the plunger against turning when the shaft is rotated and permit the plunger to be turned on the shaft to adjust the foot in relation to the anvil. 80

5. In a caliperig device, a frame, a pair of measuring members comprising a movable plunger and an anvil, a ball and socket joint connecting the anvil and frame, a rotatable shaft, a threaded connection between the shaft and plunger, a guide-collar frictionally engaging the plunger, and means to hold the collar against rotation, whereby 85 the plunger may be adjusted on the shaft in relation to the anvil and held against turning when the shaft is rotated. 90

6. In a caliperig device, an anvil, a handle, a reciprocating plunger carrying a measuring foot, a scale and revoluble pointer, a screw-shaft threaded to the plunger and carrying the pointer and a fixed pinion, gear connections between the pinion and handle, a gear wheel loose on the shaft, a spring-pressed pawl on the gear wheel to 100 engage the pinion, a governor actuated by the gear wheel to cushion the return-stroke of the plunger, and a return-spring put under tension when the plunger is raised. 105

7. In a caliperig device, an anvil, a handle, a reciprocating plunger carrying a measuring foot, operating connections between the plunger and handle including a screw-shaft threaded to the plunger, a scale, a revoluble pointer on the shaft, a gear 110 wheel loose on the shaft, a pawl and ratchet connection between the shaft and gear wheel, a return-spring for the plunger, and a centrifugal governor actuated by the gear wheel to cushion the spring-actuated stroke 115 of the plunger.

8. In a caliperig device, an anvil, a reciprocating plunger carrying a measuring foot, a scale and a revoluble pointer therefor, a screw-shaft carrying the pointer and 120 threaded to the plunger, an actuating shaft, gear-connections between the shafts, a handle, connections between the handle and actuating shaft constructed to positively move said shaft when the handle is moved from its normal position and to provide return lost motion between these parts, and a return-spring put under tension when the actuating shaft is moved from its normal position. 125

9. In a caliper device, an anvil, a reciprocating plunger carrying a measuring foot, a scale, a screw-shaft threaded to the plunger and having a revoluble pointer above the scale, an actuating shaft having a flat face, gear connections between the shafts, a handle having an angular portion engaging the face of the actuating shaft in the normal position of the parts, and a return-spring 10 for the actuating shaft.
10. In a caliper device, a frame having an anvil and an upper block, a casing on the block having a scale, a reciprocating plunger carrying a measuring foot, a screw-shaft threaded to the plunger and carrying a pointer above the scale, an actuating shaft, 15 gear connections between said shafts, a handle having front and rear stops constructed to abut on the block, and connections between the handle and actuating shaft con- 20
- structed to provide lost-motion between these parts when the handle is returned to its normal position.
11. In a caliper device, an anvil, a reciprocating plunger carrying a measuring foot, a screw shaft threaded to the plunger and having a pointer, an actuating shaft having a handle, gear connections between the shafts constructed to turn the screw shaft a plurality of times for each stroke 25 of the actuating shaft, a dial plate having a scale for said pointer and a curved slot in its body, a supplemental scale on the dial plate adjacent said slot, and a pointer mounted on the actuating shaft and co-operating with said supplemental scale. 30
- In testimony whereof I affix my signature.

WM. D. LA BATT.
